UNITED STATES PATENT OFFICE.

HARRY A. DOUGLAS, OF BRONSON, MICHIGAN.

ELECTRICAL CONNECTER.

Application filed October 20, 1923. Serial No. 669,789.

To all whom it may concern:

Be it known that I, HARRY A. DOUGLAS, citizen of the United States, residing at Bronson, in the county of Branch and State 5 of Michigan, have invented a certain new and useful Improvement in Electrical Connecters, of which the following is a full, clear, concise, and exact description.

My invention relates to circuit connecting 10 clips, the clip of my invention being adapted to effectively grip wire throughout a substantial portion of its length to insure firm mechanical assembly of wire and clip and perfect continuity of the circuit portion 15 thereof.

The clip of my invention comprises a U shaped piece of sheet metal having one side inclusive of a lateral portion which is curled against the opposite side of the clip base.

In the preferred embodiment of the invention the clip is apertured in its ends to receive a bolt which serves to clamp the sides of the clip toward each other and to further curl the curled lateral portion to further 20 wrap the clip at its base portion firmly about the wire that is laid within and against the base portion of the clip and through the bore jointly formed by the base portion and the curled clip side portion. There are preferably two such lateral curled clip side portions at one side of the clip and between which the apertured portion of this clip side 25 is disposed. The clamping bolt or binding screw which is employed to hold the wire in place thus performs its function throughout an appreciable length of the wire and through the intermediation of a curled clip portion which is further curled by the clamping 30 screw into tight engagement with the wire.

The invention will be more fully explained in connection with the accompanying drawing in which Fig. 1 is a longitudinal sectional view of a circuit continuing device 45 equipped with clips of my invention; Figs. 2 and 3 are cross sectional views respectively taken on lines 2-2 and 3-3 of Fig. 1; Fig. 4 is a longitudinal sectional view of another 50 form of circuit continuing device equipped with clips of my invention; Fig. 5 is a view of the inner end of the plug entering into the structure of Fig. 4; Fig. 6 is a view illustrating a blank piece of sheet metal 55 capable of being shaped into the clip of my invention; and Fig. 7 is a perspective view

of the clip with a continuing portion thereof broken away.

Like parts are indicated by similar characters of reference throughout the different figures.

The two forms of circuit continuing devices illustrated are each inclusive of a metallic cylindrical shell 1 formed at each end with bayonet channels 2, 2' respectively adapted to receive bayonet pins 3 and 4 respectively provided upon contact carriers 5 and 6. The contact 5 is illustrated in the form of an incandescent lamp whose filament 7 is connected in circuit when both contact carriers are assembled by the shell 1, as 65 will more fully appear. The contact carrier 6 is in the form of a connecting plug which carries two contact terminals 8 and 9 which are in the form of metallic strips extending lengthwise through the insulating body portion of the plug and which are formed at their outer ends with the wire attaching clips of my invention.

The structure of Fig. 1 is a so-called single pole device, the lamp base having a metallic 80 sheath 10, constituting one terminal of the lamp filament 7, and engageable with the metallic shell 1 which is grounded. The base of the lamp is provided with a central inner contact which constitutes the remaining terminal of the filament and is engaged with an outwardly spring pressed contact 12 which is co-axial with the shell. The contact 8, in the structure of Fig. 1, is in electrical connection with a metallic sheath 13 85 surrounding this contact carrier and also engageable with the shell 1. The other contact 9, in this structure, is bent at its inner end to project across the axis of the shell to be engageable by another outwardly 90 spring pressed contact 13 which is co-axial with the shell and contact 12 and electrically connected with the latter by the spring barrel 14 and the spring 15 that is disposed within this barrel and which is interposed between 100 the contacts 12 and 13 to press the same outwardly.

The structure of Fig. 4 is a so-called two pole device. The filament 7 in this structure has two contacts 16 and 17 upon the inner 105 end of its base that are respectively engageable by the outwardly spring pressed contacts 18 and 19. These contacts are electrically connected, respectively, with outwardly spring pressed contacts 20 and 21, 110

the springs 22, 23, pressing the contacts outwardly. In the structure of Fig. 4 the inner ends of contacts 8 and 9 are bent outwardly respectively to engage contacts 20 and 21.

5 The contacts 8 and 9 terminate at their outer ends in clips 24 and 25 of my invention. Each of these clips is preferably an integral continuation of the contact provided therewith and is of U shape. The sides of 10 each clip are formed with apertures 26, 27 to receive a clamping bolt or screw 28, the aperture 27 being threaded to receive the bolt. Each clip receives a wire 29 in its base portion. One side of each clip has the 15 straight portion 30 which contains the aperture 26, and two outer lateral portions 31 which are curled into proximity with and preferably permanently against the opposite side of the clip base. When the clamping 20 device 28 is tightened, the curled clip side portions are further curled to grip the wire

passed through the clip bore throughout a substantial length of the wire to make a perfect mechanical and electrical union between the wire and clip.

25

It is obvious that changes may be made without departing from the spirit of my invention.

Having thus described my invention I claim as new and desire to secure by Letters 30 Patent the following:

A wire receiving clip comprising a U shaped piece of sheet metal apertured in its ends to receive a bolt and having one side inclusive of an intermediate portion, which 25 is the apertured part of this clip side, and two outer lateral portions which are curled against the opposite side of the clip base.

In witness whereof, I hereunto subscribe my name this fourth day of October A. D., 40 1923.

HARRY A. DOUGLAS.
